(57) **CLAIM**

The ornamental design for an operator for a switchblade, as shown and described.

DESCRIPTION

FIG. 1 is a perspective view of the operator;
 FIG. 2 is a front view of the operator;
 FIG. 3 is a rear view of the operator;
 FIG. 4 is a left side view of the operator;
 FIG. 5 is a right side view of the operator;
 FIG. 6 is a top view of the operator;
 FIG. 7 is a side view of the operator in the context of a switchblade; and,
 FIG. 8 is a perspective view of the operator in the context of a switchblade.

The dotted lines shown in FIGS. 1-8 are environmental only and form no part of the claimed design.

1 Claim, 6 Drawing Sheets(56)
